(57) **CLAIM**

What is claimed is the ornamental design for a handle and strap device, as shown and described.

DESCRIPTION

FIG. 1 is a perspective view showing the top and right side of a first embodiment of a handle and strap device.

FIG. 2 is a top view of the first embodiment of the handle and strap device.

FIG. 3 is a rear view of the first embodiment of the handle and strap device.

FIG. 4 is a right side view of the first embodiment of the handle and strap device.

FIG. 5 is a left side view of the first embodiment of the handle and strap device.

FIG. 6 is a bottom view of the first embodiment of the handle and strap device.

FIG. 7 is a front view of the first embodiment of the handle and strap device.

FIG. 8 is a perspective view showing the top and right side of a second embodiment of a handle and strap device.

FIG. 9 is a top view of the second embodiment of the handle and strap device.

FIG. 10 is a rear view of the second embodiment of the handle and strap device.

FIG. 11 is a right side view of the second embodiment of the handle and strap device.

FIG. 12 is a left side view of the second embodiment of the handle and strap device.

FIG. 13 is a bottom view of the second embodiment of the handle and strap device; and,

FIG. 14 is a front view of the second embodiment of the handle and strap device.
